UNITED STATES PATENT OFFICE

LEANDER LARSON, OF THE UNITED STATES ARMY, KIRKLAND, ILLINOIS

AIR BRUSH

Application filed September 22, 1927. Serial No. 221,346.

(GRANTED UNDER THE ACT OF MARCH 3, 1883, AS AMENDED APRIL 30, 1928; 370 O. G. 757)

The invention described herein may be used by the Government, or any of its officers or employees in prosecution of work for the Government, or by any other person in the United States, without payment to me of any royalty thereon.

This invention relates to improved apparatus for applying liquids to surfaces by means of air pressure, and particularly to an apparatus known as an air brush or paint gun adapted to apply paint or other liquids to a surface by means of a stream of air under pressure.

The objects of the invention are the provision of a device of the above character, in which the controlling means for the flow of paint and air are convenient to the operator, are of simple construction, may be readily separated for cleaning purposes, and may be economically manufactured.

A further object is to provide a construction wherein, not only the flow of air and liquid are separately controlled, but provision is made whereby the relative lifting power or vacuum created by a given current of air flowing through the air jet, may be increased or diminished, thereby providing for the variations in viscosity of the fluid to be lifted and atomized.

Similar numerals indicate corresponding parts in all the figures of the attached drawings, and with the following description, setting forth in detail, a certain embodiment of the invention, such disclosed means constituting, however, one of the various forms in which the principle of the invention may be used.

Fig. 1 is a view showing the improved air brush and its attachments.

Fig. 2 is an enlarged longitudinal section of the air brush.

Fig. 3 is a detail elevation of the air jet, showing its interior, outlined in dots.

Fig. 4 is a similar view of the adjustable nipple.

Fig. 5 is a detail side view with parts dotted, showing the body portion without attachments.

Reference now being had to the drawings by numerals, 6 represents the surface to be

painted, 7 the paint gun or air brush, 8 the source of fluid pressure supply shown diagrammatically, 9 the paint or other liquid supply container and 10 and 11 flexible fluid and liquid supply pipes or tubes, respectively.

With special reference to Fig. 2, it will be seen that the air brush, consists of the hollow main body portion 12, having a lateral extension 13 approximately centrally located, said extension being internally threaded, in which the fluid supply cut-off valve 14 in the paint line is mounted.

The body portion 12, is provided with a vacuum chamber 15 with which the liquid inlet communicates and is at its ends, internally screw threaded, as shown at 16 and 17.

Into opening 16, is threaded an adjustable nipple 18, said nipple being provided with the outlet opening 19 and a concave outer face 20 surrounding the opening, the latter aiding in the diffusion of the spray. The interior of the adjustable nipple 18, directly back of the opening 19, is abruptly tapered to a large bore or cavity 21 which is in connection with and forms a part of the vacuum chamber 15.

The vacuum chamber 15 is located in the body portion, into which the air jet nozzle projects.

The air jet member 22, consists of a rear or outer portion 23, preferably of the same outer dimensions as the body portion 12, having an externally screw threaded portion 24 adapted to enter the body 12. A tapered nozzle 25 extends from the threaded portion 24, and enters the vacuum chamber when the parts are assembled. Said vacuum chamber consists of the space surrounding the nozzle 25, and the cavity 21 within the nipple, which is in communication with the lateral liquid inlet passage. The bore of the air jet member is tapered toward its outlet end and terminates in a small opening, surrounding said opening in the end of the nozzle, is a cut back or dish shaped portion 26 adapted to spread the blast of air, said formation of the nozzle, and the nipple at their outlets being for the purpose of producing a perfect mixture of air and liquid to form a vapor.

In the arrangement of the parts as shown,

a cut-off valve 27 is provided in the air line adjacent to the jet member, whereby the operator may have convenient control of the flow of air.

5 In operation it has been found that at times a constant intensity of air blast or other fluid is desired, but, due to the various viscosities of the paint or other liquids to be lifted, the power of the blast of air must be increased to 10 overcome the greater weight or sluggishness of the liquid.

It is obvious that a jet of air required to lift by vacuum and properly atomize a liquid such as a wall sizing or other thin solution 15 of low viscosity, will not under the same conditions be sufficient to lift and atomize a heavy paint or varnish, and it is by providing means whereby the capacity of the air blast may be controlled, that the lifting and 20 atomizing of liquids of different densities, with a jet of constant volume and velocity, is accomplished.

The parts above described provide for the diminishing or increasing of the capacity of 25 the vacuum chamber and the distance between the nipple orifice, and the discharge opening of the air jet nozzle.

The adjustments referred to are both accomplished simultaneously by the adjustment 30 of the nipple 18. By moving the nipple inwardly, the capacity of the vacuum chamber is reduced, and the nozzle discharge opening is brought closer to the nipple discharge opening, thus increasing the lifting power of the 35 air jet and intensifying atomization, the two combining to compensate for a heavier demand due to the thicker and denser liquids to be lifted, atomized and discharged against the surface to be treated.

40 By reference to Fig. 5 the extreme simplicity of the device may be better understood and consists of a body portion or T head having a centrally located lateral extension, each bored to intersect and tapped. Into one end 45 of the head the nipple of simple construction is threaded, into the other the air jet of simple construction is threaded, said simple and inexpensive parts when connected by stock valves and flexible tubing, to air and liquid 50 sources, provide an air brush or paint gun that has by extensive use proved to be a construction of great efficiency and economy.

What is claimed and desired to be secured by Letters Patent is:

55 1. A device of the class described consisting of a body portion, having a threaded axial bore, a lateral extension having a threaded axial bore in communication with said first mentioned bore, an air jet member 60 threaded into the body portion from one end and a nipple having a restricted portion in its bore and adapted to be threaded into the body portion at its opposite end for adjustment to and from said air jet, said parts 65 when assembled, adapted to provide a vac-

uum chamber in the body portion of variable sizes, for increasing or diminishing the lifting power of the air blast.

2. A device of the class described consisting of a body portion, having a threaded axial bore, a lateral extension having a threaded axial bore in communication with said first mentioned bore, an air jet having an enlarged outer end threaded into the body portion and having a nozzle extending approximately to the opposite end of the body portion, an adjustable nipple mounted in said opposite end of the body portion provided with a bore having a restricted portion into which said air nozzle extends, said parts when assembled adapted to provide a vacuum chamber in the body portion of variable size for increasing or diminishing the lifting power of the air blast. 70 75 80

3. A device of the class described consisting of a body portion, having an axial bore, a lateral extension having an axial bore in communication with said first mentioned bore and adapted to convey liquid to said bore, an air jet member having a tapered bore mounted to enter the body portion from one end and seal same, and a nipple having a restricted discharge orifice adjustably mounted in the body portion at its opposite end and adapted to receive the end of the air jet, said parts when assembled adapted to provide a vacuum chamber within the body portion of variable size, for increasing or diminishing the lifting power of the air blast. 85 90 95

4. A device of the class described consisting of a body portion, having a threaded axial bore, a lateral extension having a threaded axial bore in communication with said first mentioned bore, an air jet member entering the body portion from one end provided with an enlarged rear end, an intermediate screw threaded portion, and a reduced nozzle portion having a tapered bore and a flared discharge opening, the latter extending approximately entirely through the body portion, and a nipple having a restricted opening and flared portion inside and outside of said opening mounted in the opposite end of the body portion and adapted to be adjusted to and from the air jet nozzle for increasing or diminishing the power of the air blast, means for conveying liquid to the lateral extension and means for conveying fluid pressure to the air jet member. 100 105 110 115

5. A device of the class described consisting of a body portion, having an axial bore, a lateral extension having an axial bore in communication with first mentioned bore, an air jet member threaded into one end of the body portion provided with an enlarged rear end, an intermediate threaded portion adapted to enter the main body portion and a forward nozzle having a restricted portion and a flared discharge opening, and a concave portion surrounding said orifice, a 120 125 130

nipple mounted in the opposite end of the body portion, provided with a restricted portion and a flared discharge orifice, adapted for adjustment to increase and diminish

other end of the body portion adapted to control the flow of mixture of fluid and liquid from the device and means for supplying fluid and liquid to said valves.

5 the distance between the discharge orifice of the nozzle and the discharge opening of the nipple, to increase or diminish the lifting power of the air blast.

LEANDER LARSON.

70

6. A device of the class described consisting of a body portion, having an axial bore, a lateral extension having an axial bore in communication with said first mentioned bore, an air jet member having a discharge opening mounted in the body portion at one end, having a screw threaded portion fitting the bore of the body member and a reduced nozzle portion of a diameter less than that of the bore of the body portion to provide a vacuum chamber adjacent to the axial bore of the lateral extension, a nipple having a restricted passage and a flared discharge opening mounted in the opposite end of the bore of the body portion and adapted to be adjusted in relation to the nozzle to increase and diminish the capacity of the vacuum chamber and the relative positions of the discharge end of the air nozzle and the discharge opening of the nipple to increase and diminish the lifting power of the air blast, and means for conveying liquid to the bore of the lateral extension, means for conveying fluid under pressure to the air jet member, and means for controlling said flow of liquid and fluid.

75

35 7. A device of the class described consisting of a body portion having a threaded bore and a lateral extension having a threaded bore in communication with said first mentioned bore, a valve mounted in the lateral extension adapted to control the flow of liquid to the device, a fluid pressure jet having a tapered bore and a flared discharge and threaded into and rigidly mounted in one end of the body portion, a valve mounted in the jet adapted to control the flow of fluid to the device, a discharge nipple, having a restricted bore, adjustably threaded into the other end of the body portion adapted to control the flow of mixture of fluid and liquid from the device and means for supplying fluid and liquid to said valves.

80

35 7. A device of the class described consisting of a body portion having a threaded bore and a lateral extension having a threaded bore in communication with said first mentioned bore, a valve mounted in the lateral extension adapted to control the flow of liquid to the device, a fluid pressure jet having a tapered bore and a flared discharge and threaded into and rigidly mounted in one end of the body portion, a valve mounted in the jet adapted to control the flow of fluid to the device, a discharge nipple, having a restricted bore, adjustably threaded into the other end of the body portion adapted to control the flow of mixture of fluid and liquid from the device and means for supplying fluid and liquid to said valves. 100

40 8. A device of the class described consisting of a body portion having a threaded bore and a lateral extension having a threaded bore in communication with said first mentioned bore, means for controlling the flow of liquid to the device through said extension, a fluid pressure jet having a tapered bore and a flared discharge and threaded into and rigidly mounted in one end of the body portion, means for controlling the flow of fluid to the device through said jet, a discharge nipple, having a restricted bore, adjustably threaded into the 105

restricted passage and a flared discharge opening mounted in the opposite end of the bore of the body portion and adapted to be adjusted in relation to the nozzle to increase and diminish the capacity of the vacuum chamber and the relative positions of the discharge end of the air nozzle and the discharge opening of the nipple to increase and diminish the lifting power of the air

90

30 and diminish the lifting power of the air blast, and means for conveying liquid to the bore of the lateral extension, means for conveying fluid under pressure to the air jet member, and means for controlling said flow of liquid and fluid.

05

35 7. A device of the class described consisting of a body portion having a threaded bore and a lateral extension having a threaded bore in communication with said first mentioned bore, a valve mounted in the lateral extension adapted to control the flow of 40 liquid to the device, a fluid pressure jet having a tapered bore and a flared discharge and threaded into and will be secured to

104

45 and threaded into and rigidly mounted in one end of the body portion, a valve mounted in the jet adapted to control the flow of fluid to the device, a discharge nipple, having a restricted bore, adjustably threaded into the other end of the body portion adapted to control the flow of mixture of fluid and liquid from the device and means for supplying fluid and liquid to said valves.

103

5.5 8. A device of the class described consisting of a body portion having a threaded bore and a lateral extension having a threaded bore in communication with said first mentioned bore, means for controlling the flow of liquid to the device through said extension, a fluid pressure jet having a tapered bore and a flared discharge and threaded into and rigidly mounted in one end of the body portion, means for controlling the flow of fluid to the device through said jet, a discharge nipple, having a restricted bore, adjustably threaded into the
